Primary Examiner — Llorellys Martinez(74) *Attorney, Agent, or Firm* — Kyle R Satterthwaite; Ryan W Dupuis; Ade & Company Inc.(57) **CLAIM**

The ornamental design for a cap for a sunroom wall assembly, as shown and described.

DESCRIPTION

FIG. 1 is a front, top, and left side perspective view of a cap for a sunroom wall assembly showing our new design, the front, top, and right side perspective view being a mirror image thereof;

FIG. 2 is a front, bottom, and left side perspective view of the cap for a sunroom wall assembly, the front, bottom, and right side perspective view being a mirror image thereof; FIG. 3 is a front elevational view of the cap for a sunroom wall assembly, the rear elevational view being identical thereto;

FIG. 4 is a top plan view of the cap for a sunroom wall assembly;

FIG. 5 is a bottom plan view of the cap for a sunroom wall assembly; and,

FIG. 6 is a side elevational view of the cap for a sunroom wall assembly, the opposing side elevational view being identical thereto.

The cap is shown with a symbolic break in its length. The appearance of any portion of the cap between the break lines forms no part of the claimed design.
